UNITED STATES PATENT OFFICE.

EDWIN JOHANSON, OF TROY, IDAHO.

OIL CAN.

1,407,657.

Specification of Letters Patent. Patented Feb. 21, 1922.

Application filed July 12, 1919. Serial No. 311,991.

To all whom it may concern:

Be it known that I, EDWIN JOHANSON, a citizen of the United States, residing at Troy, in the county of Latah and State of Idaho, have invented new and useful Improvements in Oil Cans, of which the following is a specification.

This invention relates to improvements in oil cans, and the principal object of the invention is to provide means for causing the oil to flow from the can upon the manipulation of the valve.

Another object of the invention is to provide a spring-pressed plunger for forcing the oil from the can and means for holding the plunger in retracted position when it is desired to fill the can or for any other reason.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of the invention with parts in section;

Figure 2 is a cross section on line 2—2 of Figure 1;

Figure 3 is a cross section through the valve;

Figure 4 is a detailed view of the handle and stand;

Figure 5 is a detailed view of the valve lifter.

In these views 1 indicates the body of the can which is provided with the usual spout 2 which is removably secured to the can by the screw top 3. The bottom 4 of the can is screw-threaded to the body as shown at 5. Within the body is located a piston 6, the rod 7 of which extends through the bottom 4, a packing gland 8 being provided for preventing leakage. A coiled spring 9 is located between the piston and bottom and tends to force the piston towards the top of the can so as to force the oil in the can out of the spout.

The spout is provided with means for closing the same to prevent the discharge of oil until wanted. Such means consists of a

casing 10, extending crosswise of the spout, as shown and having one end closed and the other end open. A valve 11 closes the end of the spout at the screw top 3 and the stem 12 of said valve passes through the lower part of the spout into the casing 10 where it is provided with an enlarged head 13. The open end of the casing 10 is closed by a stopper 14 through which passes a stem 15 which is provided with an enlarged head 16. This stem is normally held in its outer position by means of the coiled spring 17 having one end pressing against the packing gland 18 and its other end against the head 16. The inner end of the stem engages the forked end of a valve lifter 19 which is carried by a clevis 20 mounted on the stopper and the other forked end of the lifter engages the head 13 of the valve stem. It will thus be seen that the spring 17 will hold the valve in closed position with the stem 15 in its outer position. The can is provided with a handle 21 provided with a finger hold 22 so located that when the same is gripped by the hand the thumb will be in position to press upon the head 16 of the stem 15 to push the same inwardly and thus rock the valve lifter to move the valve off its seat and thus open the spout. The pressure of the spring 9 upon the piston will force the oil through the spout. When enough oil has been discharged the thumb is removed from the head 16 so that the spring 17 will return the parts to normally 90 position and close the valve.

The stem 7 of the piston is provided with a shoulder 23 to limit the upward movement of the piston and the rod also carries at its outer end a combined handle and stand 24 by which the piston may be lowered by hand and which forms a rest for the can.

When the can is to be filled or it is desired to hold the piston at the bottom of the can, the same may be lowered by hand and locked by means of a catch 25 slidably mounted on the bottom of the can engaging a hole 26 in the stem.

In order to prevent a vacuum being formed in the rear of the piston I provide a hole 27 in the bottom of the can which is closed by a flap 28.

It is thought from the foregoing description that the advantages and novel features of my invention will be readily apparent.

I desire it to be understood that I may make changes in the construction and in the

combination and arrangement of the several parts, provided that such changes fall within the scope of the appended claims.

What I claim is:

- 5 1. A device of the character described comprising a body, a spout provided thereon, a screw top removably securing said body to the can, the bottom of the can being screw threaded to the body, and a piston located within said body and having its rods extending through the bottom thereof, a coiled spring located between the piston and the bottom of the can, means for closing the spout consisting of a casing extending crosswise of the spout and having one end closed and the remaining end open, a valve closing the ends of the spout and the screw top and the stem of said valve passing through the lower part of spout into the casing where it is provided with an enlarged head, a stopper closing the open end of the casing and a stem passing therethrough and having an enlarged head provided thereon, a coil spring adapted to hold said stem in its outer position, a packing gland pressing one end of said spring and the enlarged head pressing against the remaining end, a valve lifter having its forked ends engaged by the inner ends of said stem and a clevis carrying said lifter and the former being mounted on the stopper, and the other forked end of the lifter engaging the enlarged head of the valve stem.
- 10 2. A device of the character described com-

prising a body, a spout provided thereon, a screw top removably securing said body to the can, the bottom of the can being screw threaded to the body, and a piston located within said body and having its rods extending through the bottom thereof, a coiled spring closing the spout consisting of a casing extending crosswise of the spout and having one end closed and the remaining end open, a valve closing the ends of the spout and the screw top and the stem of said valve passing through the lower part of spout into the casing where it is provided with an enlarged head, a stopper closing the open end of the casing and a stem passing therethrough and having an enlarged head provided thereon, a coil spring adapted to hold said stem in its outer position, a packing gland pressing one end of said spring and the enlarged head pressing against the remaining end, a valve lifter having its forked ends engaged by the inner ends of said stem and a clevis carrying said lifter and the former being mounted on the stopper, and the other forked end of the lifter engaging the enlarged head of the valve stem. 55

In testimony whereof I affix my signature.

EDWIN JOHANSON.
